PRELOADING OF BOGIES FOR MOTOR CRANES AND THE LIKE

Roy H. Zeilman and Martin L. Sheetz, Elyria,
Ohio, assignors to The Thew Shovel Company,
Lorain, Ohio, a corporation of Ohio

Application June 16, 1948, Serial No. 33,308

8 Claims. (Cl. 280—104.5)

1

The present improvements, relating generally as indicated to preloading of bogies for motor cranes and the like, have more particular regard to novel preloading means designed for enabling the handling of greater loads by the crane without requiring added counterweight, shortening of the crane boom or shifting of the bogie and crane relative to one another on the vehicle chassis.

Ordinarily motor cranes are mounted on chassis commonly referred to as "six wheelers" which comprise a frame with a front axle and two rear axles suspended therefrom, the latter axles being part of a bogie of which either or both are provided with differential gearing driven through a rotary propeller shaft extending rearwardly from a gear box associated with the vehicle engine. However, insofar as the principal features of this invention are concerned, specific reference to such motor cranes and to particular bogie constructions is to be regarded as merely exemplary, it being understood that the manner and mechanism for preloading bogies herein disclosed may be equally well suited to the preloading of bogies of semi-trailers of the type adapted to be coupled with a tractor by means of the usual fifth wheel to thus constitute a so-called "tractor-semi-trailer."

It is, as indicated above, one of the principal objects of this invention to provide a novel manner and means for preloading bogies whereby to increase the load carrying capacity of a crane or the like mounted on the frame of the chassis or semi-trailer, such increased capacity being obtained without impeding bogie action, without requiring adding or shifting of counterweights on the frame, and without varying the crane operating radius.

Other objects and advantages will become apparent as the following description proceeds.

To the accomplishment of the foregoing and related ends, the invention, then, comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a perspective view of the rear portion of a truck chassis illustrating a preferred embodiment of the present invention in association with the bogie suspended from said chassis;

2

Fig. 2 is a schematic side elevation view of the bogie preloading mechanism;

Fig. 3 is a schematic representation of a typical motor crane without the present improvements thereon;

Fig. 4 is a view similar to Fig. 3 in all respects except that the present improvements are associated therewith; and

Fig. 5 is a rear elevation view of a portion of a bogie preloading mechanism of a slightly modified form.

Referring now to the drawing, and first more especially to Fig. 1 thereof, there is illustrated therein the rear portion of a "six wheeler" comprising a frame 1 including longitudinally extending side rails 2 and 3 and cross members 4 and 5 projecting laterally beyond said side rails to provide outrigging adapted to be blocked for lifting loads from the sides of the frame.

Suspended from said frame 1 is a bogie 6 of any desired construction, herein shown as comprising a pair of rockers or walking beams 7 pivoted about trunnions 8 on opposite sides of said frame, said trunnions being preferably disposed, as best illustrated in Fig. 2, in line or slightly below the centers of the front and rear axles 9 and 10 respectively fastened to the opposite ends of said rockers whereby to eliminate or counteract the "pole vaulting" effect otherwise encountered when the brakes of the two pairs of wheels 11 and 12 on said axles are applied. In the particular bogie 6 illustrated herein the rear axle 10 thereof is provided with differential gearing driven by a rotary propeller shaft 14 extending forwardly of the frame to a gear box (not shown) which is disposed rearwardly of the vehicle engine.

The bogie 6 just described may be either of the single suspension type wherein the parts denoted by the numeral 7 are leaf springs pivotally connected to trunnions 8 fixed on the frame or alternatively of the type in which the parts 7 are rigid beams pivotally connected to trunnions 8, the load being carried by springs interposed between said frame and trunnions. Other types of bogies which may be employed with the preloading mechanism to be presently described include the reach member construction in which is provided a rigid reach member from axle to axle to which leaf springs are clipped at the middle, said springs being shackled at their ends to the frame; the separate spring suspension type in which the inner ends of separate springs for each axle are joined by an equalizer bar pivoted to the frame; the radius rod type in which radius rods pivoted

close to the trunnion serve to position the axles and to transmit brake torque, and the other well known types employing equalizer bars, bell cranks, parallelogram, and other torque rod systems.

The front end of the truck is of a conventional form comprising a cab 15 (see Figs. 3 and 4) and an engine thereunder (not shown) supported on said frame 1 and a front axle suspended from said frame and carrying the pair of steerable wheels 16 thereon.

Supported on an intermediate portion of said frame 1 for rotary movement thereon on a turntable or other suitable means and either self-propelled or through the truck engine, usually the latter, is a crane generally designated by the numeral 17 in Figs. 3 and 4, said crane including an operator's compartment 18 therein, said crane 17 and cab 15 being preferably so formed that the crane may be positioned with its pivoted boom 19 extending forwardly and alongside said cab 15 as when the truck is traveling from one job to another. Within said crane compartment 18 is the usual two-drum arrangement when hoisting is to be done with a hook or a magnet, one drum being employed for raising and lowering the boom 19 and the other drum being employed for raising the load attached to the hook or magnet. Obviously additional drums may be required if a grab-bucket or the like is employed.

Referring now to the bogie preloading mechanism, the same comprises front and rear pairs of longitudinally spaced brackets 20 and 21 on said side rails 2 and 3, said pairs of brackets being disposed on opposite sides of the trunnions 8 and fixed on the respective side rails by bolting, welding, or other suitable means. Journalled in the pairs of brackets 20 and 21 are the opposite ends of torsion spring bars 23 and 24.

Adjacent each end of said bars 23 and 24 and non-rotatable thereon as through a splined or axially serrated connection are inwardly directed pairs of front levers 25 and rear levers 26 having pairs of front and rear drag links 27 and 28 respectively connected to their inner ends, said front drag links 27 in turn having their lower ends connected to the opposite ends of an equalizer bar 29 and said rear drag links 28 having their lower ends connected to the opposite ends of an equalizer bar 30. Said equalizer bars 29 and 30 are respectively pivoted at their centers on the front and rear axles 9 and 10 of said bogie 6. The connections of the drag links 27 and 28 with the equalizer bars 29 and 30 and levers 25 and 26 are preferably of the complementary ball and socket type widely used in the automotive industry.

Said drag links 27 and 28 are rendered adjustable in length as by providing end members 31 and 32 respectively formed with lefthand and righthand threads in which are threaded the opposite ends of a bolt 33, rotation of said bolt thereby providing a turnbuckle adjustment of said drag links.

Predetermined adjustment of the above-described bogie preload mechanism may be effected as follows:

(1) The front and rear levers 25 and 26 are mounted on the associated torsion spring bars 23 and 24 so as to be disposed at a predetermined angle corresponding to the desired degree of preloading.

(2) The front drag links 27 are then adjusted so that when the front axle 9 of the bogie is in its normal position, intermediate its uppermost

and lowermost positions, as shown in Figs. 1 and 2, said front equalizer bar 29 and said front levers 25 will be in a horizontal position, the rear levers 26 then being inclined downwardly at an angle corresponding with the desired amount of preloading as aforesaid.

(3) The rear drag links 28 are then adjusted to twist the bars 23 and 24 until the rear levers 26 are parallel with the front levers 25, said rear equalizer bar 30 then being parallel with the front equalizer bar 29.

With such above adjustments made, it is now evident that the rear drag links 28 will be under compression and that the front drag links 27 will be under tension respectively exerting downward force on the rear axle 10 and wheels 12 and upward force on the front axle 9 and wheels 11. With respect to the bogie action, it can be seen that the front axle 9 and wheels 11 thereon in moving upwardly will permit an untwisting of the bars 23 and 24 thereby reducing the severity of shocks when the front wheels encounter a road bump. On the other hand, movement of said front axle 9 and wheels 11 downwardly will effect a further twisting of said bars 23 and 24 to thus increase the tension on the front drag links whereby the contact pressure between the front wheels and the pavement will be still further reduced. It is to be observed that the bogie action as to the raising and lowering of the wheels 11 relative to one another and similarly of the wheels 12 relative to one another is not in any way interfered with. As is apparent, the equalizer bars 29 and 30 are operative to distribute excessive loads from one wheel to the others.

Following is a list of the formulae which may be used for determining the proper size of the bars 23 and 24, together with a typical sample calculation for predeterminedly preloading a bogie.

$$(1) D = \frac{2SLR}{Gd}$$

$$(2) d = \frac{2SLR}{GD}$$

$$(3) W = \frac{Gd^4 D}{10R^2 L}$$

$$(4) S = \frac{Gd^2 D}{2LR}$$

$$(5) d^4 = \frac{10R^2 WL}{GD}$$

W = Load in lbs.

S = Stress in lbs. per sq. in.

L = Length of Spring Bar (23 and 24) = 68".

R = Lever (25 and 26) Length = 7 1/2".

G = Modulus of Torsional Elasticity 11,000,000

d = Dia. of Spring Bar 23 and 24 in inches.

D = Deflection in inches at end of levers 25 and 26.

Assuming that the weight on each bogie axle 9 and 10 is 19,300 lbs. in the running position, the maximum compression and tension loads exerted by the preloading mechanism must be less than such amount when the spring bars 23 and 24 are deflected a maximum amount. Further, assuming a maximum deflection of 2 1/2" upward and downward of each axle and a preload of 7,000 lbs. varying between 5,000 and 9,000 lbs. at the minimum and maximum deflections, the rate of the spring bars 23 and 24 must each be 2,000 lbs./2.5" or 800 lbs. per inch which in turn requires a total deflection of 9,000/800 or 11.25".

Now, using formula (3) above, the diameter of the spring bar can be calculated as follows:

$$W = \frac{11,000,000 \times d^4 \times 11.25}{10 \times 56.25 \times 68} = 9000\#$$

$$d^4 = \frac{10 \times 56 \times 68 \times 9000}{11,000,000 \times 11.25} = 2.775$$

$$d = 4\sqrt{2.775} = 1.291"$$

Then, using formula (4) with deflections of 8.75, 6.25, and 11.25, the following stresses are obtained, viz.:

$$\text{Preload Stress} = \frac{11,000,000 \times 1.291 \times 8.75}{2 \times 68 \times 7.5} = 122,000\#/\text{Sq. In.}$$

$$\text{Minimum Stress} = \frac{11,000,000 \times 1.291 \times 6.25}{2 \times 68 \times 7.5} = 87,000\#/\text{Sq. In.}$$

$$\text{Maximum Stress} = \frac{11,000,000 \times 1.291 \times 11.25}{2 \times 68 \times 7.5} = 157,000\#/\text{Sq. In.}$$

Thus the spring bars 23 and 24 may be fabricated from chrome vanadium steel for example properly heat treated and shot peened to raise the elastic limit to 175,000-265,000 lbs. per sq. in. which is adequate for the above noted stress range of 87,000 per sq. in. to 157,000 lbs. per sq in.

With an axle distance of 52" and a distance of 120" from the center of rotation of the crane to the hook thereof, or 93" from the trunnions 8 to the hook, the maximum additional load regardless of where the connections are made on the axles which it is possible to lift at any distance is the amount caused by the couple in the frame, which in this case amounts to 52" $\times$ the load in the spring divided by any distance selected from the center line of the couple to the center line of the load. Therefore, the increase in static lift will be $52 \times 14,000/93 = 7840$ lbs., and the increase in moving lift will be $52 \times 10,000/93 = 5,370$ lbs.

As a further example, a comparison of Figs. 3 and 4 will reveal that the installation of the present preloading mechanism without any other changes effects an increase of 8,300 lbs. additional capacity, viz. 41,800 minus 33,500. In Fig. 3 the tipping line of the chassis is at the trunnions of the bogie whereas the effect of the preloading mechanism thereon, as shown in Fig. 4, is to shift such tipping line rearwardly in direct proportion to the ground reactions $24,767 + 52,767$ of the bogie wheels or 77,534 lbs. whereupon $77,534/24,767 = .32$ or 32%, and $77,534/52,767 = .68$ or 68%. Then 68% of 4,333 feet, the axle distance of the bogie, or 2,946 feet is the tipping line distance from the front bogie axle 9. Thus, the new tipping line moves rearward .780', viz. the difference of 2.946' and 2.166'. The new moment of stability is equal to 44,034 lbs. $\times$ 6.653' or about 292,000 foot lbs., and the radius to the load is then equal to 6.970' whereupon the lifting capacity with the boom head of Fig. 4 is 292,000 foot lbs./6.970' or 41,800 lbs., thereby providing an increased capacity of 8,300 lbs. over the 33,500 lbs. as shown in Fig. 3. The diagrams in Figs. 3 and 4 represent a substantially balanced condition except for a 15% safety factor as indicated by the figure 2770# at the front end of the chassis.

With reference to Fig. 5, the same illustrates a modification in which a hydraulic cylinder 34 is

substituted for the rear drag link 28, said cylinder being actuatable at will and with a desired variable pressure in line 35 (connected to said cylinder and leading from a pump or the like) to effect predetermined preloading. With such substitution it is more convenient to preload the bogie during use of the crane and to relieve the preloading at all other times. In this modification, a cylinder 34 may be associated with each of the rear drag links 28 or optionally with each of the front drag links 27 and simultaneously actuated to equally preload both spring bars 23 and 24.

Although certain difficulties are encountered in the application of fluid cylinders for preloading, it has been found that in some instances it may be feasible to effect the desired rearward shifting of the tipping line of the frame 1 relative to the trunnions 8 by the interposition of a fluid cylinder between the rockers 7 or extensions thereof or on either or both of the axles 9 and 10 and the frame 1 at a point spaced from said trunnions for the purpose of producing a turning moment or moments opposite to that effected by a load on the crane tending to tip the frame. The magnitude of such counter-moments may be controlled either by the pressure of the cylinder motivating fluid or by the use of a compressible fluid such as air, for example. In the case of incompressible fluids, blocking of the lines of the cylinder by a valve or the like effects shifting of the tipping line of the frame to the rear axle 10 and wheels 12 thereby enabling handling of very heavy loads by the crane but of course with correspondingly greater loads on the rear axle 10 and wheels 12.

From the foregoing, it is now understandable that the provision of a preloading mechanism such as illustrated and described effectuates a substantial increase in the load carrying capacity of the crane or other lifting device without the necessity of adding further counterweight 36 or shifting thereof on the frame, or of shortening the operating radius of the boom 19, or of relatively shifting the bogie 6 and crane 17 on the frame. In addition, it is apparent that this preloading mechanism has utility with various forms of bogies other than that illustrated whether on motor cranes as illustrated or on semi-trailers and the like.

Other modes of applying the principle of the invention may be employed, change being made as regards the details described, provided the features stated in any of the following claims or the equivalent of such, be employed.

We therefore particularly point out and distinctly claim as our invention:

1. The combination with a vehicle frame and a plural axle bogie suspended therefrom, of a preloading mechanism interconnecting said frame and bogie and operative to exert upward force on one axle and downward force on another axle, said mechanism comprising a torsion spring bar journaled in said frame, spaced levers non-rotatable on said bar, and links connecting one lever with one axle and another lever with another axle, at least one of said links comprising an extensible hydraulic cylinder assemblage operative when actuated to predeterminedly twist said bar.

2. The combination with a vehicle frame and a plural axle bogie suspended therefrom, of a preloading mechanism interconnecting said frame and bogie and operative to exert upward force on one axle and downward force on an-

other axle, said mechanism comprising a pair of torsion spring bars on said frame, equalizer bars pivotally connected between their ends to said one and another axle respectively, and links connecting said spring bars with the opposite ends of said equalizer bars.

3. The combination with a vehicle frame and a plural axle bogie suspended therefrom, of a preloading mechanism interconnecting said frame and bogie and operative to exert upward force on one axle and downward force on another axle, said mechanism comprising a pair of torsion spring bars journaled in said frame, spaced levers on each bar non-rotatable thereon, equalizer bars pivotally connected between their ends to said one and another axle respectively, and links connecting said levers with the opposite ends of said equalizer bars, at least one of said links being extensible whereby to predeterminedly twist both of said spring bars.

4. The combination with a vehicle frame and a plural axle bogie suspended therefrom, of a preloading mechanism interconnecting said frame and bogie and operative to exert upward force on one axle and downward force on another axle, said mechanism comprising a pair of torsion spring bars journaled in said frame, spaced levers on each bar non-rotatable thereon, equalizer bars pivotally connected between their ends to said one and another axle respectively, and links connecting said levers with the opposite ends of said equalizer bars, at least one of said links comprising an extensible hydraulic cylinder assemblage operative when actuated to predeterminedly twist both of said spring bars.

5. The combination with a vehicle frame and a two axle bogie including an axle connecting member pivoted between its ends to said frame, of a pair of torsion spring bars on said frame extending longitudinally thereof above said axle connecting member, equalizer bars pivotally connected between their ends to said axles respectively, and links connecting said spring bars with the opposite ends of said equalizer bars.

6. The combination with a vehicle frame and a two axle bogie including an axle connecting member pivoted between its ends to said frame, of a pair of torsion spring bars on said frame extending longitudinally thereof above said axle connecting member, spaced levers on each bar

non-rotatable thereon, equalizer bars pivotally connected between their ends to said axles respectively, and links connecting said levers with the opposite ends of said equalizer bars.

5 7. The combination with a vehicle frame and a two axle bogie including an axle connecting member pivoted between its ends to said frame, of a pair of torsion spring bars on said frame extending longitudinally thereof above said axle connecting member, spaced levers on each bar non-rotatable thereon, equalizer bars pivotally connected between their ends to said axles respectively, and links connecting said levers with the opposite ends of said equalizer bars, at least 10 one of said links being extensible whereby to predeterminedly twist both of said spring bars.

8. In combination, a vehicle frame, a support for the front end of said frame, a support for the rear end of said frame comprising a two-axle bogie including front and rear axles and an axle connecting member pivoted between its ends to said frame, and a preloading mechanism interposed between said frame and said bogie and comprising a torsion spring bar mounted on said frame and connected to said axles and twisted to exert downward force on said rear axle and upward force on said front axle thereby imposing a force moment on said frame whereby to increase the load carrying capacity of said frame insofar as loads disposed rearward of the pivot of said member are concerned.
